(57) **CLAIM**

The ornamental design for an interchangeable disposable foil pan/cover, substantially as shown and described.

DESCRIPTION

FIG. 1 is a top perspective view of a interchangeable disposable foil pan/cover showing my new design;

FIG. 2 is a reduced top plan view of the interchangeable disposable foil pan/cover of FIG. 1;

FIG. 3 is a reduced bottom plan view of the interchangeable disposable foil pan/cover of FIG. 1;

FIG. 4 is a front view of the interchangeable disposable foil pan/cover of FIG. 1 with the rear plan view being a mirror image thereof;

FIG. 5 is a right side plan view of the interchangeable disposable foil pan/cover of FIG. 1; and,

FIG. 6 is a left side plan view of the interchangeable disposable foil pan/cover of FIG. 1.
